[57] CLAIM

The ornamental design for a cribbage board or the like, as shown and described.

DESCRIPTION

FIG. 1 is a perspective view of the cribbage board or the like showing my new design of the present invention with two mirror-image halves folded into the closed position;

FIG. 2 is a side elevational view of the game board of FIG. 1;

FIG. 3 is a top plan view of the game board of FIG. 1;

FIG. 4 is a perspective view of the game board of FIG. 1 with two mirror-image halves opened;

FIG. 5 is a front elevational view of the game board of FIG. 1.

The lock seen in FIGS. 3 and 5 has been omitted from the remaining figures for ease of illustration.
